PROCESS FOR THE PREPARATION OF TARTARIC ACID VALUES

Solomon Soltsberg, Tamaqua, Pa., assignor to Atlas Powder Company, Wilmington, Del., a corporation of Delaware

No Drawing. Application May 20, 1942,
Serial No. 443,694

4 Claims. (Cl. 260--528)

The present invention relates to the nitric acid oxidation of carbohydrates to dibasic acids, and more particularly to the oxidation of glucose-containing carbohydrate material to produce tartaric acid.

An object of my invention is to provide a more efficient and economical process for oxidizing carbohydrates, particularly glucose, or a polysaccharide capable of yielding glucose on mild acid hydrolysis, to the industrially valuable tartaric acid.

A further object of the invention is to produce a relatively high tartaric acid yield from carbohydrates.

Another object is to provide a process easy to control, economical of equipment and safe to operate.

Other objects will become apparent from the following description.

The controlled oxidation of glucose or its polymers to give high yields of tartaric acid is inherently a difficult problem. To get d-tartaric acid, a gluconic chain must be cut selectively between the 4 and 5 carbon atoms, which scission also yields oxalic acid, a valuable by-product. For the highest yield of oxalic acid compatible with production of theoretical tartaric acid, it should be the only point of attack. That is, the theoretical yields of tartaric and oxalic acids from the oxidation of glucose are 83.3% and 50% respectively based on the glucose. Thus:

My investigations show that the oxidative decomposition of glucose by nitric acid can simultaneously follow several paths. The primary oxidation products seem to be gluconic and saccharic acids, but 2- and 5-ketogluconic acids can occur. These intermediates in turn can be broken down to give 5-carbon and 3-carbon acids in addition to meso- and d-tartaric and oxalic acids. The tartaric acids and all materials containing 2 or more carbon atoms can be broken down further to oxalic acid and carbon dioxide.

Tartaric acid is ordinarily one of the more easily attacked oxidation products, and, consequently, oxidation normally proceeds beyond it to oxalic acid. In the presence of directive catalysts, however, oxidation has been carried out so as to produce tartaric acid. So far as is known, however, processes for the nitric acid oxidation of carbo-

hydrates to tartaric acid have not heretofore proved commercially operative. As a result of my study of the reaction it appears to me that this is largely due to inherent process inefficiency and resultant lack of reproducibility of results.

Since tartaric acid is an intermediate product of reaction and the reaction proceeds so complexly and by different mechanisms, a reacted solution contains a number of different products of differing stages of oxidation. Those present to the greatest degree are the ones most resistant to nitric acid under the conditions employed. Usually if catalysts directive for tartaric acid are employed, the oxidation yields a mixture of tartaric acid, oxalic acid, and a residue of acids of lower stages of oxidation which appears largely to be made up of saccharic acid. Tartaric acid, of course, is present only to the extent that it has not been further oxidized to oxalic acid and carbon dioxide. In any given oxidation to produce tartaric acid, a considerable quantity of the tartaric acid formed during the reaction is decomposed. This decomposition could be eliminated and yield improved if tartaric acid could be removed from the solution as it is formed and before any opportunity for attack upon it by nitric acid. In practice, however, this is impossible since there are no available separation procedures for the cheap removal of small increments of tartaric acid from the nitric acid solution.

Another loss of potential tartaric acid has been in the residue of intermediate oxidation products. It has been proposed to oxidize the residue further after removal of tartaric and oxalic acids, and some improvement in overall yield has been effected by this means. However, such procedure has not adequately remedied inefficient performance in the first oxidation step, and the second oxidation has been difficult to perform. It has necessitated a second and entirely different set of operating conditions and resulted in further losses of tartaric acid by destructive oxidation and a further residue of partially oxidized material.

As an oxidizing agent nitric acid possesses the advantages of cheapness and regenerability, but its action depends upon a complex decomposition to nitrous acid and oxides of nitrogen so that the oxidizing power varies continually and in a manner very difficult of exact control throughout the period of use. Its reaction with carbohydrate materials is autocatalytic which makes control of temperature and concentration difficult to achieve. The reaction proceeds at first with too great violence and then tapers off as nitric acid becomes used and oxidation products formed. The violent phase of the oxidation must be kept in hand if the reaction is to proceed to good yields of the desired products. Processes heretofore proposed have not accomplished adequate

control of the oxidation and as a result have been inefficient.

I have invented a process which is more efficient, subject to better control, more economical and safer to operate than the previously known processes for making tartaric acid from carbohydrate material. First, my process is carried out in cyclic manner. In each cycle I oxidize both fresh carbohydrate and residue from a previous oxidation with nitric acid. The reaction is preferably performed under carefully controlled and stage-wise conditions. Residue from each cycle is oxidized with fresh carbohydrate in each next succeeding cycle, and so on.

By operating in my manner a number of advantages are achieved. The oxidation of the mixture of partially oxidized material and fresh carbohydrate proceeds more evenly and completely to produce the desired product. All residue is subjected to further oxidation so that no material capable of forming tartaric acid or oxalic acid, the recoverable by-product, is wasted, and the reaction proceeds with but one set of constantly repeated conditions. I have found that by operating so as to obtain a smaller conversion per pass I am able to obtain a greater overall yield over a succession of cycles. This represents a removal of tartaric and oxalic acids at an earlier stage in the oxidation, and, hence, approaches the ideal of removing these acids as they are formed. The conversion per cycle should be sufficient, however, to permit adequate removal of product.

I have found a number of features of procedure and reaction control are important to the obtention of optimum yields. For starting material I may use water-soluble carbohydrate materials oxidizable in solution by nitric acid to carbon dioxide, tartaric acid and other soluble compounds, and a residue containing intermediates further oxidizable to tartaric acid. By the term "carbohydrate material," I mean to include not only compounds containing hydrogen and oxygen in the proportions of water but also other polyhydroxylic materials, such as hexitols, pentitols, erythritol, sugar acids, including aldonic and ketonic acids, other similar materials and materials readily hydrolyzable to these. Such materials are now commonly classed with carbohydrates. Most hexoses, such as fructose or mannose, and particularly d-glucose which is available in pure form free from ash, of constant composition, and at a low price, are readily usable in my process. Carbohydrate materials readily hydrolyzable by acid to other starting materials are equivalent to those materials. Among such materials, I include oligo- or poly-saccharides, such as starch, dextrine, corn syrup, sucrose and highest molasses (partially inverted raw can sugar) which readily hydrolyze to hexoses. Butadiene dioxide which hydrolyzes readily to erythritol may also be used in my process. An available and advantageous group of starting materials is that composed of glucose, fructose, the pentoses, gluconic acid, erythritol, 5-ketogluconic acid, and materials which rapidly hydrolyze to these. I cannot use, and exclude from my invention, galactose which oxidizes to insoluble mucic acid, nor can I use, and, hence, I exclude other carbohydrates which oxidize to insoluble intermediate products, for insolubles are not practically further oxidizable in my reaction. With the exception of d-glucose and sucrose, the at present commercially available saccharides (economically useful) have relatively high ash contents. The ash content causes difficulty in a cyclic process

due to build-up in the residue and usually not as many cycles can be performed. Sucrose while obtainable ash-free gives lower yields of d-tartaric than does glucose. It is understood that 5 various less desirable saccharide materials can be rendered suitable as starting materials by proper deashing or demineralizing as, for example, by ion exchange methods.

I may introduce nitric acid oxidizing agent 10 into the reaction mixture as such, in which case I prefer that it contain a little lower oxide of nitrogen which appears to act catalytically toward the reaction; or I may form it in situ by passing into the reaction mixture a mixture of oxidizable nitrogen oxides and air or other oxygen containing gas or by using higher oxides of nitrogen which have been formed outside the reaction mixture.

The reaction requires a catalyst to give a practical yield of tartaric acid. Any oxidation catalyst specific for tartaric acid product, a number 20 of which are known in the art, can be used. Various polyvalent metal compounds are operative for this purpose, including compounds of vanadium, manganese, iron and molybdenum. Vanadium in the form of its soluble pentavalent compounds, such as sodium orthovanadate hexadecahydrate ($Na_3VO_4 \cdot 16H_2O$) is a most efficient catalyst and is preferred by me. Using the preferred catalyst, 30 sodium orthovanadate hexadecahydrate, the most efficient quantity has been found to lie in the range 0.01 to 0.03% of the fresh sugar. A fresh quantity of catalyst should be added with each quantity of carbohydrate material, that is, 35 at the start of each oxidation in the series.

The oxides of nitrogen evolved from the reaction, which contain somewhat less than 10% nonrecoverable nitrogen as N_2 or N_2O , can be converted to nitric acid, without further purification, either at atmospheric pressure, or, after compression, as for example, to the customary 40 6-7 atmospheres; or they may be oxidized and absorbed in the reaction mixture.

The oxidation process is carried out on a commercial scale suitably in stirred, stainless steel reactors fitted with internal cooling coils, and a means for recovering the nitric acid fumes evolved.

Control of the various operating variables is 50 necessary for uniform operation and optimum yields. Uniform operation, in turn, calls for approximately constant residue composition and an approximately constant total feed composition, hence, an approximately constant carbohydrate-residue ratio. The amount and composition of the residue are determined by the independent operating variables, such as acid-carbohydrate ratio, catalyst nature and amount, initial acid strength, heating schedule, and, to a minor extent, equipment design. Of these, the acid-carbohydrate ratio is preferably used for control. As the cyclic process is initiated with 60 fresh carbohydrate and built up to equilibrium, the composition of the residue, and, hence, its behavior on oxidation, changes somewhat until after several cycles, the equilibrium point is reached where substantially constant tartaric acid yields are obtained.

When this equilibrium is reached, the size of the residue, and hence the point to which the oxidation has been carried, is controlled, of course, to give the optimum yield of tartaric acid. As has been noted above, the best possible yield of tartaric acid would require removal of the acid as formed, and one of the important advantages

of this process is that by recycling partially oxidized material it permits a closer approach to this ideal. However, limitations on the amount of material which can be conveniently recycled and the amount of product necessary for a practical separation do limit the extent to which the ideal is practically obtainable. I have found that with glucose good yields may be obtained by controlling oxidizing conditions so that a weight ratio of residue to fresh glucose of from about 0.5 to about 1.0 is maintained. This residue-glucose ratio for equilibrium recycling conditions, is achieved by using an acid-glucose mol ratio of from about 5 to 7.5 and preferably about 6 to about 7.5 mols of 100% nitric acid per mol of glucose, and holding the other operating conditions within the limits hereinafter disclosed.

When starting up the cycle, and glucose alone is being oxidized, the ratio should be about 5, and this should be gradually increased for successive cycles, to a point between about 6 and 7.5 (determined by batch size and the characteristics of the reaction vessel), until the cycle is in equilibrium. The initial aqueous nitric acid concentration in the reaction mixture should preferably be from 45-70% HNO₃ (calculated as aqueous HNO₃ without reference to amount of sugar and/or residue). The effect of changing this concentration is reflected principally in the violence of the reaction. The oxidation of carbohydrate to tartaric acid will proceed with nitric acid as weak as 15%, but the yields are inferior to those obtainable with higher acid strengths, and the reaction times much longer. Similarly, nitric acid stronger than 62-63%, up to 70%, can be used, but the yields are not as good, and the reaction becomes much more difficult to control.

The control of temperature in the oxidation is highly desirable to insure uniformity of product and yield and also to make the reaction largely independent of external heating by conserving the heat generated by the reaction. I have found it of considerable advantage to conduct the reaction in a series of temperature stages. During the mixing of ingredients I prefer to maintain a low temperature of about 20° C. or lower. Following mixing, the temperature should be raised gradually or allowed to rise spontaneously to about 30 to 35° C. This period is called the induction or heating-up stage. The length of the heating-up stage is subject to considerable variation and may be shortened by the addition of a nitrite radical or by heating. By prolonging it the violence of the "blow" stage described below may be moderated, but the time necessary for the oxidation is thereby increased. During the heating-up period intermediate oxides of nitrogen are formed from the nitric acid. The presence of intermediate oxides or acids derived therefrom is necessary for the reaction. A period of 20 to 40 minutes represents a desirable compromise between these conditions under the reaction conditions I employ. When the temperature reaches 30 to 35° C. an autocatalytic and, at least at first, strongly exothermic reaction called the "blow" sets in. The temperature rapidly rises and under most operating conditions it is necessary to cool the reactants strongly so that the temperature does not exceed 75° C. for more than a short time. The "blow" stage is maintained at a temperature of about 50-75° C., and preferably at 65-70° C., for a period of time the length of which is not critical (but should be constant for uniform results) and may be determined empirically for operating convenience. Generally

this stage of the reaction will be allowed to proceed from 45 to 120 minutes. The final temperature stage of the oxidation is the "fume-off" stage in which the last of the nitric acid is reacted and passed off as lower nitrogen oxides. Absence of nitric acid and nitrogen oxides is necessary for efficient recovery of products from the reaction mixture. During the "fume-off" stage the reaction mixture is maintained at a high temperature somewhat below the boiling point of the mixture, say at 90 to 95° C. until nitrogen oxides are no longer detectable in the fumes. The nitrogen oxides can be identified by odor, or, more practically, by test with starch-iodide indicator paper.

Stagewise temperature control during oxidation is not essential to the reaction, for it might be carried out isothermally. Stagewise operation, however, has been found to shorten materially the total time of reaction; also, it aids reaction control. Furthermore, stagewise operation permits temperature conditions more nearly appropriate to the different oxidation stages.

Optionally my process, at least at certain stages, 25 may also be operated either under reduced or superatmospheric pressure.

The oxalic and tartaric acids can be recovered from the oxidized reaction mixture partly, in the case of oxalic acid, by direct precipitation, by 30 ester separation as described below, and by a number of known methods such as by crystallizing in the form of acid potassium salt, zinc salts, calcium salts or lead salts, although for practical reasons one type of recovery may be preferred 35 over another. My cyclic process is of definite benefit regardless of the recovery step used.

Methods of operation are illustrated by the following examples:

EXAMPLE 1

RUN 1

An initial, non-cyclic oxidation, to prepare an 45 oxidizable residue for use in a cyclic series, was performed as follows:

50 500 grams crystalline, anhydrous d-glucose were dissolved in 875 cc. chilled 70% nitric acid. To this solution were added 19 cc. aqueous solution containing 0.075 gram sodium orthovanadate hexadecahydrate as catalyst. The entire solution was then transferred to a water jacketed stainless steel reactor and 140 cc. water were added. At this time the acid had a strength of 62% and was present in the ratio of 5 mols acid to 1 mol glucose. Heating was started and the temperature of the solution rose to 32° C. in the course of 78 minutes. Then the "blow" commenced. The temperature of the solution was controlled by passing cooling water through the jacket of the reactor so that it did not exceed 76° C. (except for a short time at the start when the reaction was most violent). Thereafter the solution was kept at 65-70° C. for 90 minutes and then heated at 94-96° C. on a water bath, until nitrogen oxides were no longer detectable by test with starch-iodide paper. It required over 6 hours to drive off the HNO₃ completely.

70 The above constituted the preparation of an oxidized mixture. The oxidized product was then cooled for 24 hours at 5° C., after which a crop of 97.3 grams crystalline oxalic acid was removed by filtering. 41.5 grams of basic zinc carbonate were added to the filtrate (equivalent to 15% of the total titratable acidity) to precipitate residual dissolved oxalic acid as the zinc salt. After fil-

tering to remove the zinc oxalate, a further 138.5 grams of basic zinc carbonate were added to the filtrate with stirring at 45-55° C. to precipitate the tartaric acids as zinc salts. After filtering off the zinc tartrates the filtrate was concentrated by evaporation and a residue syrup weighing 375 grams recovered which contained about 90% solids.

Recovery data for this run are listed in the table below as Run 1.

RUN 2

The next run, a cyclic oxidation run, was started with the 375 grams of residue syrup recovered in Run 1. This residue syrup was mixed with 500 grams fresh d-glucose and dissolved in 1051 cc. 70% nitric acid. A fresh portion of sodium orthovanadate solution was used to provide 0.015% catalyst (calculated as hexadecahydrate) based on sugar. The entire solution was transferred to the reactor and the acid concentration adjusted to 62% by adding water as in Run 1. Reaction was induced by heating the solution as in Run 1. In this case, however, the "blow" started in 55 minutes at 31.0° C. at which time cooling water was run through the jacket and the temperature controlled to a maximum temperature of 52.5° C. The rate of heat evolution in this "blow" was substantially milder than the corresponding stage of Run 1. The HNO_3 fume-off was conducted as before and the oxidized product worked up to remove oxalic and tartaric acids as in Run 1. Recovery of the residue in this case yielded a syrup (about 90% solids) weighing 505 grams, for recycling.

Subsequent runs were made according to the procedure of Run 2, nine runs constituting the series. Nitric acid initial strength was adjusted as necessary in these runs by dilution with water to give 62-63% solutions. The ratio of acid to sugar and residue was adjusted from run to run to keep the weight of residue fairly constant. If the residue appeared to be increasing the next oxidation was given a higher acid ratio, and vice versa.

The following table gives the results for the nine run series just described. Run 1 was not cyclic and is therefore omitted from the calculation of averages.

Table I

Run #	Yield of tartaric acid (calculated from Zn salt) per 100 g. sugar	Yield of oxalic acid dihydrate, (total of free acid and amount of acid calculated from Zn salt) per 100 g. sugar	Residue syrup weight	Mols HNO_3 /mol. sugar	Max. "blow" temp.
1	26.6	25.6	375	5	76
2	38.9	35.7	505	5+1.0	52.5
3	45.0	41.7	533	5+1.49	55.0
4	45.0	46.5	575	5+1.49	47.0
5	38.9	49.5	635	5+1.49	53.0
6	30.6	48.4	650	5+1.84	54.0
7	61.3	55.3	580	5+1.84	43.0
8	51.6	48.9	543	5+1.84	61.0
9	43.7	39.2	550	5+1.49	59.0
Av. 2-8	43.7	45.4	569	6.86	

The cycling can be continued indefinitely using pure glucose, the amount and nature of the residue reaching a steady state. Hence, while the acid strength or ratio to sugar and residue may have to be varied slightly during the first few cycles, while the system is approaching the steady

state, at the latter stage all factors can be held substantially constant.

The process of the invention results in favoring the production of the more valuable tartaric acid over the less valuable oxalic acid. Operating with d-glucose the tartaric acid yields (calculated from yields of separated salts) have been found to average more than 42% under preferred conditions such as those illustrated in Example

1. The oxalic acid yields average about 44% (as oxalic acid dihydrate). Furthermore the process is readily controllable, much less violent, and considerably safer to operate than the prior oxidation processes.

By means of my process cheap sources of glucose can be used to substantial advantage. Yields are not as good as with pure d-glucose and the number of cyclic runs is limited by the extent to which ash and the like build up in the residue. However, the cyclic process is successful for such glucose sources and under certain economic conditions it will be preferable to use this type of raw material instead of pure d-glucose. The following example illustrates one series of five runs using a crude glucose source.

EXAMPLE 2

A typical residual corn syrup obtained as a by-product in the process of preparing d-glucose from cornstarch and analyzing about 71% reducing sugar as dextrose, 4.5% ash (including sodium chloride), and 79% total solids, was used. This material is known to be a mixture of various di-, tri-, and tetraglucosides, with some glucose, and some of the acid reversion products of glucose.

The reactor was a 3-liter flask cooled by immersion in a large water bath with initial temperature of 24° C.

The initial run was performed by mixing together 746 grams of the corn syrup described, containing 600 grams solids, 1050 cc. concentrated nitric acid, 22.2 cc. water, and 0.09 grams sodium orthovanadate hexadecahydrate in 22.5 cc. water.

After mixing the ingredients, the temperature of the solution rose to 30° C. The "blow" started 25 minutes after mixing, rose to 87° C. in 3 minutes, and was then kept at 65-70° C. for 45 minutes by running cooling water into the water bath. The flask was then removed from the water bath and the temperature permitted to rise spontaneously (reaching about 90° C.). The flask was thereupon packed in sawdust (for heat insulation) until the nitric acid had been driven off by the heat generated by the reaction.

Oxalic and tartaric acids were thereafter removed from the product of this oxidation by the method of Example 1. The residue obtained after concentrating the remaining liquid consisted of 450 grams solids.

For the second run (first cyclic run) the residue was combined with a fresh 600 gram portion of the same corn syrup, 1312 cc. of 70% nitric acid, and 0.12 gram sodium orthovanadate hexadecahydrate in 30 cc. water. The "blow" started in 30 minutes and the solution reached a maximum temperature of 82.5° C. The reaction was controlled and nitric acid removed as in Run 1.

Oxalic and tartaric acids were removed as before and the remaining liquid concentrated to yield a residue syrup (about 90% solids) for recycling.

Three further cyclic runs were made following the same procedure. The details and recovery figures for these five runs are tabulated below,

Run 1 being the non-cyclic oxidation first described:

Table II

Run #	Yield of tartaric acid (calculated from Zn salt) per 100 g. sugar	Yield of oxalic acid dihydrate (total of free acid and amount of acid calculated from Zn salt) per 100 g. sugar	Residue syrup weight	Mols HNO ₃ /mol. sugar	Max. "blow" temp.
1	18.92	19.54	450	5	87
2	29.20	38.20	572	5+1.25	82.5
3	30.66	52.10	700	5+1.85	87
4	27.70	42.20	755	5+1.85	86
5	30.86	43.60		5+1.85	86.5
Av. 2-5	29.6	44.02			

The accumulation of ash in the corn syrup series limits the number of cycles to about 5. The residue of the fifth run can be used in another cyclic series by removing the ash by suitable procedures. Alternatively, the residue of the fifth run can be oxidized without adding more sugar to it and a further amount of product, principally oxalic acid, obtained.

The average yields of the cyclic process in Example 2 are 29.6% tartaric acids and 44.02% oxalic acid. For comparison, the residue from a single oxidation (not cyclic) was reoxidized and a total yield of 27.7% tartaric acids and 41.6% oxalic acid obtained from both. This stepwise oxidation is not only less efficient with respect to yield but is a longer process involving more steps and also a more expensive process to practice.

The cyclic process of this invention can be carried out with lower concentrations of nitric acid than are shown in the preceding examples.

EXAMPLE 3

The process of Example 1 was carried out with 50% initial concentration of nitric acid instead of 62-63%, but with other conditions of temperature and catalyst the same. The ratio of acid to sugar was increased progressively in each of the four runs to keep the weight of residue fed back approximately constant. The oxalic and tartaric acids were separated as the zinc salts. 400 g. batches of glucose were run using a stainless steel reactor. The following table lists data for the initial oxidation (Run 1) and two cyclic oxidations according to this process:

Table III

Run #	Yield of tartaric acid (calculated from Zn salt) per 100 g. sugar	Yield of oxalic acid dihydrate (total of free acid and amount of acid calculated from Zn salt) per 100 g. sugar	Residue syrup weight	Mols HNO ₃ /mol. sugar	Max. "blow" temp.
1	26.58	29.86	323	5	77.5
2	29.35	49.45	625	5+1.25	65.0
3	42.49	39.75	304	5+1.50	68.0

In the runs of Example 3, owing to the dilution, the blow was much less vigorous, the temperature did not rise as high, and a much longer period was required for the boil-off. Nevertheless, the characteristic improvement in tartaric acid yield from the recycling was evinced.

The zinc salts of oxalic acid can be worked up for saleable oxalic acid values by treatment with

soda ash to produce sodium oxalate and regenerate the basic zinc carbonate, or by other known methods. The zinc tartrates can be converted to free tartaric acids, (a mixture of d- and meso in which the d- predominates) by treatment with oxalic acid, and the free acids resolved, either by fractional crystallization of the free acids or by means of the acid potassium salt.

The recovery of oxalic and tartaric acids may likewise be effected in a similar manner by means of their calcium salts.

I have discovered a third method of product removal which I call ester-separation. This method is particularly useful where the products of my reaction are desired in the form of esters such as dibutyl tartrate or where it is desired to avoid contamination with inorganic compounds. In this ester separation the mixture of acids resulting from the oxidation are esterified by ordinary esterification procedures to produce diesters of lower alcohols, such as those having less than 6 carbon atoms and particularly butyl alcohol. For example, the butyl ester may be prepared by refluxing the reacted solution with butyl alcohol and permitting water to distill off. The esters of the tartaric and oxalic acids are then separated from the other esters as by solvent extraction, for example with benzene or by vacuum distillation. The residual esters are then converted back to free acids or lactones, as by acid or alkaline hydrolysis, and returned to the oxidation process for recycling. The oxalic and tartaric esters may be utilized directly as such, or likewise converted to the free acids by acid or to salts by alkaline hydrolysis.

The above examples have all described oxidation carried out in batch operation. However, my process can also be conveniently operated in a continuous manner. For example, nitric acid, carbohydrate material and residue may be continuously fed into a reaction system made up of successive zones in which are maintained temperature conditions corresponding to the desired temperature stages such as the blow and fume-off periods, and solution from which recovery of product is to be made may be continuously drawn off. Under continuous operation I have found the heating-up stage may usually be merged with the blow.

Optimum conditions vary for different types of carbohydrate starting materials used, but in every case cyclic operation is easier to control, gives higher yields, and is more economical to practice than the separate oxidation of the residues.

Hence, my process is not necessarily limited to the specific examples shown, but is of general applicability to various types of carbohydrate oxidation to tartaric acid, and is to be held as limited only by the scope of the appended claims.

Having described my invention, what I claim is:

1. A cyclic process for the production of tartaric acid values which comprises oxidizing in aqueous solution a mixture of a carbohydrate material selected from the group consisting of glucose, fructose, pentoses, gluconic acid, 5 ketogluconic acid erythritol, and materials rapidly hydrolyzable to these by dilute nitric acid; and an oxidation residue from a previous oxidation, with nitric acid, in the presence of a soluble vanadium compound catalyst specific for tartaric acid production, conducting the reaction in a series of temperature stages comprising a prior stage conducted substantially entirely at a temperature of not more than approximately 75° C. and a later stage conducted at a temperature of at least ap-

proximately 90° C. and below the boiling point of the reaction mixture until evolution of nitrogen oxides ceases, removing tartaric and oxalic acids from the reaction, thereby leaving said oxidation residue, adding additional carbohydrate material to said residue and repeating the cycle.

2. A process according to claim 1 wherein the carbohydrate material is d-glucose and the ratio of residue to d-glucose is within the range of from approximately 0.5 to approximately 1.0.

3. A process according to claim 1 wherein the carbohydrate material is d-glucose and the ratio of residue to d-glucose is within the range of from

approximately 0.5 to approximately 1.0, and within the range of from approximately 5 to approximately 7.5 mols of nitric acid per mol of glucose are employed for the reaction.

4. A process according to claim 1 wherein the tartaric and oxalic acids are removed from the reacted mixture by esterification of the acids in the reacted mixture with a lower alcohol, separating the tartaric and oxalic esters from the esters of other acids in the reacted mixture, hydrolyzing the said esters of other acids to reform those acids thereby forming the residue.

SOLOMON SOLTZBERG.
